UNITED STATES PATENT OFFICE

2,640,410

APPARATUS FOR AIR VOLUME CONTROL IN
VENTILATING SYSTEMSGeorge K. Raider and Edmund J. Little, Chicago,
Ill., assignors to The Pyle National Company,
Chicago, Ill., a corporation of New Jersey

Application December 2, 1949, Serial No. 130,734

7 Claims. (Cl. 98—10)

1

This invention relates generally to a method and apparatus for controlling air volume in a ventilating system and more particularly relates to improvements in a ventilating arrangement for a railroad car or the like wherein a plurality of enclosures are serviced by individual pressure-displacement panel units, a system in which a predetermined pressure-volume relationship must be accurately maintained to produce uniform air distribution throughout the entire car.

According to the general features of the present invention, a railway car provided with a plurality of room enclosures, such as bedrooms, roomettes or compartments, as well as a corridor or an access aisle running therethrough, is equipped with duct means extending substantially the entire length of the car and adapted to carry pressurized, temperature-conditioned ventilating air. The duct means may be considered as defining a primary plenum chamber.

The primary plenum chamber is provided with a plurality of outlets, there being at least one outlet for each enclosure within the railway car, and a total displacement air control valve is placed in control of each respective outlet to admit controlled volumes of air from the primary plenum chamber through the outlets.

A secondary plenum chamber is provided in registry with each outlet, one wall of the secondary plenum chamber comprising a perforated distribution plate which may conveniently form part of the interior of the enclosure to be ventilated. The air from the primary plenum chamber enters the secondary plenum chamber at reduced pressure and low velocity and may be further diffused by the distribution plate upon being displaced into the enclosure. In this manner, ventilating air is supplied to each enclosure without detectable drafts and without objectionable noise due to the sound of rushing air.

In the event that ventilating requirements for each individual enclosure vary, the occupant of the enclosure may adjust the individual panel unit to vary the volume of air admitted to the enclosure. It is contemplated by the present invention that variations in pressure and volume occurring within the primary plenum chamber because of variable adjustments effected in individual enclosures will be fully compensated by controlling the volume of air supplied in the primary plenum chamber so as to maintain substantially constant the pressure of the air delivered to the individual panel units.

It is an object of this invention to provide a

method of ventilating a plurality of enclosures whereby the supply of ventilating air may be stabilized.

Another object of the present invention is to provide a ventilating system suitable for furnishing conditioned air to a plurality of enclosures and incorporating regulating means for controlling the volume of air in the system so as to maintain substantially constant the pressure of the air within the system.

Another object of the present invention is to provide an improved ventilating system arrangement for a railway car or the like wherein the operation of the ventilating system may be substantially stabilized through the controlled recirculation of ventilating air to a transition duct communicating with an access aisle or with the atmosphere, or both.

Yet another object of the present invention is to provide improved volume control apparatus incorporating a unique relief valve assembly.

It is believed that the methods of operation contemplated by the present invention will be best understood from the description of the apparatus provided for practicing same.

Many other features, advantages and additional objects of the present invention will become manifest to those versed in the art upon making reference to the detail description which follows and the annexed sheets of drawings in which:

Figure 1 is a somewhat schematic cross-sectional plan view of a railway car having a ventilating system according to the present invention;

Figure 2 is a side elevational enlarged detail view with parts in section showing a pressure-sensitive relief valve according to the present invention;

Figure 3 is an end elevational view partly in section showing the valve of Figure 2 as seen from a plane transverse to the sectional plane of Figure 2;

Figure 4 is a fragmentary schematic view of an alternative arrangement for a ventilating system contemplated by the present invention;

Figure 5 is a fragmentary schematic view of an additional alternative embodiment according to the present invention;

Figure 6 is a fragmentary schematic view of yet an additional embodiment of the present invention;

Figure 7 is a fragmentary cross-sectional view of a railway car showing additional details of construction of the ventilating system of the present invention;

Figure 8 is an enlarged detail view with parts

removed showing constructional details of a remote control device employed; and

Figure 9 is a side view of the device shown in Figure 8.

As shown on the drawings:

Although the present invention finds useful application in other environments, it is of particular utility when employed in connection with the ventilation of a plurality of crowded enclosures requiring the provision of large volumes of ventilating air which must be furnished without detectable drafts and without objectional noise due to the sound of rushing air.

A particularly advantageous type of ventilating system for accomplishing these ends is shown in Figures 1 and 7.

A plurality of enclosures may be provided within in a railway car indicated generally by the reference numeral 10, the enclosures including a number of bedrooms indicated by the reference numeral 11 and a number of smaller compartments, such as roomettes, which are indicated by the reference numeral 12.

An access aisle 13 runs along the length of the car 10 so that persons entering either end of the car 10 upon the platform 14 may gain entrance to the respective enclosures.

In the construction of the car, duct means 16 are preferably incorporated in the roof section of the car so as to define a primary plenum chamber 17 extending substantially the entire length of the car.

Duct means 18 defining a transition chamber 19 may be provided at one end of the duct means 16 in communication with the primary plenum chamber 17.

The transition chamber 19 may be provided with a fresh air intake 20 extending through each side of the car 10 to atmosphere and a recirculating air intake 21 which, in the embodiment of Figure 1, is in communication with the corridor or aisle 13.

Pressurizing means in the form of a motor 22 and a fan 23 are employed to furnish pressurized air from the transition chamber to the primary plenum chamber 17.

It will be understood that the usual conditioning elements may be provided so that only clean filtered temperature-conditioned air will be furnished to the primary plenum chamber 17. However, for the sake of convenience and clarity, conditioning elements are shown diagrammatically at 24.

The duct means 16 is provided with a plurality of outlets, there being at least one outlet for each bedroom 11 and each roomette 12.

Each enclosure may be provided with a panel control unit "P" for effecting pressure-displacement of ventilating air from the primary plenum chamber 17 into the enclosure proper. Such panel control units are preferably constructed along the lines more particularly described in connection with my copending application, Serial No. 4,368, filed January 26, 1948, now U. S. Patent No. 2,580,835.

A total displacement valve, including an adjustably movable valve plate 26 pivotally supported on a hinge 27, operates to control the admission of air from the primary plenum chamber 17 through a diffuser 28 into a secondary plenum chamber 29 defined by duct means 30. A perforated distribution plate 31 may form a common wall between the secondary plenum chamber 29 and the enclosure to be ventilated,

the perforated distribution plate 31 forming a part of the decorative treatment achieved within the enclosure.

Air entering the secondary plenum chamber 29 will be at reduced pressure and at low velocity and may be further diffused through the perforated distribution plate 31 so as to be furnished to the enclosure without detectable drafts and without excess movement likely to produce the sound of rushing air.

The valve plate 26 is normally biased toward an open position by a spring 47. However, the position of the valve plate 26 relative to the outlet opening may be selectively varied by the occupant of the enclosure through a remote control device indicated generally by the reference numeral 48 (Figures 6-9).

A Z bracket 49 may be affixed to the valve plate 26 to cooperate with a wire 50 sheathed by a cable 51 leading to the control device 48. The end of the wire is connected to a rack 52 as at 53. The rack 52 may be actuated upon turning a knob 54 affixed to a gear 56 meshed with rack 52. A click spring 57 is provided to stabilize the gear assembly. Limit stops 58 are fastened to the wire 50 to cooperate with the abutment 59 movable with the rack 52.

According to one embodiment of the present invention, the duct means 16 is provided with an additional outlet 32 which is in communication with the corridor or aisle 13 (Figure 2). In order that the ceiling portion of the car structure in the corridor or aisle 13 may be unbroken, the outlet 32 is preferably filled in with a perforated panel 33.

A pressure-sensitive relief valve is provided to control the flow of air from the primary plenum chamber 17 outwardly through the outlet 32 into the corridor or aisle 13.

In the preferred embodiment herein shown and described, the duct means 16 comprises a duct which is generally rectangular in cross-section. A valve plate 34, also substantially rectangular in cross-section, is provided, the valve plate having a dimension of greater length than the corresponding height of the duct 16 so as to be positionable therein on a plane displaced from the vertical to close the duct and thereby control the flow of air therethrough.

A hinge 36 is affixed to one edge of the valve plate 34 and to one wall of the duct means 16 so as to pivotally support the valve plate 34. The opposite edge of the valve plate 34 rests on the opposite wall of the duct means 16.

It will be apparent that one face of the valve plate 34 is exposed to pressures developed within the primary plenum chamber 17. These pressures will operate to pivotally displace the valve plate 34 against the components of force due to the weight of the valve plate tending to hold the same in closed position.

In order to substantially counterbalance the valve plate 34 and sensitize the responsiveness thereof to the variations in air pressure within the plenum chamber 27, a movably adjustable counterweight 37 is provided. The counterweight 37 may be adjustably positioned relative to a vertical reference plane passing through the pivot axis of the valve plate 34 so as to operate on a radial lever arm extending through the pivot axis. Support means may be provided for the counterweight 37, this particular embodiment showing a web 38 attached in firm assembly to the plate 34 and having an arcuate slot 38a suitable for passing a threaded stud 37a there-

through. The counterweight 37 may be adjustably positioned anywhere along the length of the slot 38a by tightening a nut 37b on the threaded stud 37a.

In operation, even though the volume controls in individual spaces are altered, delivery of ventilating air to the other spaces will not be changed because the valve plate 34 will open in response to incremental increases in pressure within the primary plenum chamber 17 to dump the necessary quantity of air into the corridor or aisle 13 through the outlet 32 to maintain air pressure in the primary plenum chamber 17 substantially constant.

By virtue of this arrangement, the corridor or aisle 13 functions virtually as a recirculating line since the volume of air dumped through the outlet 32 may eventually find its way back through the corridor intake 21 and into the transition chamber 19.

In Figure 4, a modification of the arrangement shown in Figure 1 is illustrated wherein the duct means 16 is provided with an outlet 39 leading directly to the transition chamber 19. A valve 40 is placed in control of the outlet 39 and may be actuated by a suitable motor mechanism indicated generally by the reference numeral 41 operating through a linkage 42. The motor mechanism 41 may be made responsive to pressure variations by energizing the motor mechanism 41 through appropriate conductors 43 leading to a pressure-sensitive control 44. In this embodiment, excess volumes of air will be bypassed to the transition chamber 19 upon any incremental increase of pressure within the primary plenum chamber 17.

In the embodiment of Figure 5, valve means 46 are provided to control the volume of air admitted to the primary plenum chamber by closing the valve means 46 on the intake side of the blower 23. The valve means 46, in one preferred form, may be defined by a damper of the louver type and may be controlled, as before, through a linkage 42 operated by a motor mechanism 41 connected by conductors 43 to a pressure-sensitive control 44.

In the embodiment of Figure 6, the individual control devices 48 of each enclosure are connected by a mechanical linkage 60 to a rheostat 61. The rheostats 61 are incorporated in the energization circuit of the motor 22 shown by the conductors 62 to selectively vary the speed of the motor in response to variable demand requirements, thereby tending to maintain the pressure within the primary plenum chamber 17 constant.

Although persons skilled in the art might suggest minor modifications to our preferred embodiments, it should be understood that we do not propose to be limited to the precise details described merely for the sake of clarity but wish to embrace within the scope of this patent all such modifications as reasonably and properly come within the scope of our contribution to the art.

We claim as our invention:

1. A ventilating system for a railway car or the like comprising a plurality of enclosures to be ventilated disposed along the length of the car, an access aisle therefore, a transition duct being in communication with the access aisle and the atmosphere, a main air duct along the length of the car, means to supply ventilating air from the transition duct to the main air duct under

pressure, a plurality of control means for admitting varying volumes of air to each of the enclosures, and valve means responsive to pressure variations located between the main air duct and the access aisle to dump controlled quantities of ventilating air into said access aisle thereby to automatically maintain pressure within the main air duct at a substantially constant value.

2. A ventilating arrangement for a railway car of the type having a plurality of room enclosures and an access aisle therefor, comprising duct means along the length of the car to carry pressurized ventilating air, a plurality of control means to selectively admit variable volumes of air to each of the enclosures from the duct means, and pressure-sensitive relief valve means between the duct means and the access aisle of the car to discharge air from the duct means into the access aisle in response to pressure variations within the duct means.

3. A ventilating arrangement for a railway car of the type having a plurality of room enclosures and an access aisle therefor, comprising duct means along the length of the car to carry pressurized ventilating air, pressurizing means having an inlet in communication with the access aisle, conditioning means associated with the pressurizing means, a plurality of control means to selectively vary the volume of air admitted to each of the enclosures from the duct means, and pressure-sensitive relief valve means between the duct means and the access aisle of the car to recirculate air from the duct means through the access aisle to the pressurizing means in response to pressure variations within the duct means.

4. A ventilating system for a railway car having an access aisle and a plurality of enclosures to be ventilated disposed along the length of the car, a transition duct means at substantially atmospheric pressure and communicating with said access aisle, a main air duct along the length of the car, pressurizing means to supply ventilating air to the main air duct under pressure and being in communication with said transition duct means to obtain a portion of the supply of ventilating air therefrom, a plurality of control means for admitting varying volumes of air to each of the enclosures, and valve means responsive to pressure variations, said valve means being located between the main air duct and the access aisle to automatically return controlled quantities of ventilating air to said transition duct means and thereby maintain pressure within the main air duct at a substantially constant value.

5. A ventilating arrangement as defined in claim 2 wherein said relief valve plate means more particularly includes a pivotally mounted valve plate extending across the interior of said duct means and providing a reactor face subject to duct pressure, and adjustable counterweight means connected to said plate for selectively pivotally counterbalancing said plate for communication of said access aisle with said duct pressure at selected pressure values.

6. A ventilating arrangement as defined in claim 5 wherein said counterweight means includes a web carried by the valve plate and being substantially vertically disposed in a plane transverse to that defined by the valve plate and a mass supported by said web for adjustment relative to the pivot axis of the valve plate.

7. A ventilating arrangement as defined in claim 2, said valve means comprising a valve plate

of greater cross-sectional area than the duct means and being pivotally supported from one wall of the duct means to normally lie across the duct means on a plane displaced from a vertical reference plane extending through the pivot axis, a web carried by the valve plate and being substantially vertically disposed on a plane transverse to that defined by the valve plate, and movably adjustable counterweight means carried by the web; the counterweight means being positionable relative to the vertical reference plane to selectively variably counterbalance the weight of the valve plate, whereby the valve plate will be pivotally displaced upon predetermined increases in pressure within the duct means.
